STAND FOR A SEWING MACHINE CABINET

Edward W. Stanton, Cranford, and William Hofgesang,
Avenel, N.J., assignors to The Singer Company, a cor-
poration of New Jersey

Filed Nov. 5, 1962, Ser. No. 72,379

Term of patent 14 years

(Cl. D70—2)

FIG. 1 is a front perspective view of a stand for a sewing machine cabinet showing our new design, and FIG. 2 is a rear perspective view of the stand shown in FIG. 1.

The essential features of our design reside in the portions shown in full lines.

We claim:

The ornamental design for a stand for a sewing machine cabinet, substantially as shown and described.
